ATTORNEY

UNITED STATES PATENT OFFICE.

LINCOLN KUENEMANN, OF RAMAPO, ASSIGNOR TO WILLIAM I. WALTER, OF NEW YORK, N. Y.

DESIGN FOR A PATTERN FOR PRINTED FABRICS.

SPECIFICATION forming part of Design No. 24,096, dated March 12, 1895.

Application filed January 9, 1895. Serial No. 534,388. Term of patent 3½ years.

To all whom it may concern:

Be it known that I, LINCOLN KUENEMANN, a subject of the Queen of Great Britain, residing at Ramapo, in the county of Rockland 5 and State of New York, have invented and produced a new and original Design for a Pattern for Printed Fabrics, (Case E,) of which the following is a specification.

The leading features of my design consist 10 in the alternated and substantially parallel rows, one row comprising a series of staggered lines of angularly disposed, short and disconnected bars, the other row comprising the intermittent and juxtaposed squares and intervening short juxtaposed bars.

In the drawing forming part of this specification, the design for the pattern is shown consisting of a series of parallel rows of fig-

ures, one row A consisting of two juxtaposed squares B, and between the squares are three 20 short bars C, the rows of bars and squares alternating; the other row D consisting of three staggered lines of angularly disposed short disconnected bars E running in the same direction as the bars C of the row A; the rows 25 A and D alternating on the face of the fabric.

I claim—

The design for a pattern for a printed fabric, substantially as herein shown and described.

Signed at the city, county, and State of New York, this 3d day of January, 1895.

30 LINCOLN KUENEMANN.
